UNITED STATES PATENT OFFICE.

ALBEN E. LUNDELL, OF NEW YORK, N. Y., ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,249,146.

Specification of Letters Patent.

Patented Dec. 4, 1917.

Application filed December 2, 1916. Serial No. 134,589.

To all whom it may concern:

Be it known that I, ALBEN E. LUNDELL, a citizen of the United States, residing at New York, in the county of Bronx and State 5 of New York, have invented certain new and useful Improvements in Telephone-Exchange Systems, of which the following is a full, clear, concise, and exact description.

This invention relates to telephone exchange systems, and particularly to that type in which machine switching is employed, and in which party line ringing is accomplished through a single set of terminals per line.

15 The object of this invention is the improvement in the circuits and control of selective signaling apparatus of party lines in an automatic telephone system.

20 A feature of this invention is the provision of a double brush tripping zone in a panel type selector or connector switch, whereby the same set of brushes may be selected in one of two ways—the choice of one or the other of these two ways resulting in a 25 circuit change which defines the character of the ringing current to be transmitted to the called party line.

In a system embodying this invention, an 30 operator sets up on a register the number of the called line and a letter designating the party wanted on that line. The register is so arranged that on calls to direct lines and to the negative station of the ring side of the party line, the regular impulses are sent 35 out in the well-known manner. On calls to other stations of party lines, an additional set of five impulses is sent out with the incoming brush or with the final brush impulses, or with both, causing thereby the 40 movement of the brush rod of the incoming or the final selector to a second brush tripping zone. By means of additional trip fingers of the trip rod, the same set of brushes is tripped as would have been the case had 45 the call been for a direct line. The additional movement causes a change in the conditions for ringing, so that any of the four stations can be rung.

Heretofore, systems have been devised in 50 which such selection has been accomplished, such for instance as that disclosed in the application of Reeves and Lundell, Serial No. 73,223, filed January 20, 1916. The present invention, however, is an improvement in 55 many respects, the chief of which is the use

of the ordinary number of counting relays, instead of double the number as in the case cited.

An additional feature of this invention is the provision of means for a more reliable 60 control of registers and keys. In its broadest aspects this improvement consists in a change from a series connection to a multiple connection, which is, when a plurality of contacts are included in a circuit, an important factor in the reliability of operation.

Two relays are provided and so connected to the battery loads that when placed in series, both will be energized. The link between the two, however, consists of a multiple 70 of switches each controlled by a digit register. The arrangement of the switches is such that the actuation of any single one will result in the energization of one relay only, while the other relay will remain de- 75 energized until every switch has been actuated. The final operation of the latter relay is made to signal the completion of the setting of the registers and to initiate the further operation of the apparatus connected 80 therewith.

The drawings are arranged so that when Figure 2 is placed to the right of Fig. 1, Fig. 3 to the right of Fig. 2, Fig. 4 to the right of Fig. 3, Fig. 5 below Fig. 1 and Fig. 6 to the right of Fig. 5, a complete telephone system is diagrammatically represented. Fig. 1 represents in detail a calling subscriber's line, an operator's position, a cord circuit and a first selector switch. Fig. 5 90 represents a cord finder switch and a set of counting relays. Fig. 6 represents a register, which through the cord finder switch and counting relays, is instrumental in extending a call through the first selector. Fig. 2 represents the extension of a call from the first selector to a connecting circuit in a distant exchange and a second selector at that point. Fig. 3 represents the extension 95 of the call from the second selector to a final selector or connector switch. Fig. 4 represents the extension of the line from the connector switch to the called party line, four stations being shown on this line.

In a number of the drawings, sequence 105 switches such as 100 in Fig. 1 are shown. These switches are substantially of the construction disclosed in Patent No. 1,127,808. Each is provided with a motor magnet which, when energized, forces a rotatably 110

mounted disk into contact with a constantly rotating disk, and thereby rotates a spindle on which are mounted a number of electrical contactors. These contactors, such for instance as 101 in Fig. 1, are arranged to close a circuit in the positions indicated by the numerals adjacent thereto. Each switch is also provided with a control contactor, such as A¹, which is so arranged that an energizing circuit is completed through the motor magnet in all positions except those indicated by the numerals adjacent thereto.

In Figs. 2 and 3 brush tripping mechanism is represented which is substantially similar in construction to that disclosed in Patent No. 1,177,044. Each selector switch is provided with a set of multiple brushes, and mechanism is provided whereby any desired set of brushes may be put in operation.

Referring now especially to Fig. 1, we may assume a call to be initiated by the subscriber at substation S. The action of this subscriber in removing the receiver from its switch-hook results in the establishment of a circuit from ground, the right-hand winding of line relay LR, the inner armature and contact of cut-off relay CO, through one limb of the subscriber's line to and through the apparatus of the substation S, through the other limb of the subscriber's line, contact and outer armature of cut-off relay CO, the left-hand winding of line relay LR to battery and thence to ground. This results in the energization of line relay LR, whereupon a circuit is established from ground, to contact and armature of line relay LR, the line lamp LL to battery and thence to ground.

The operator whose circuit is designated by the numeral O, upon observing the lighting of lamp LL, inserts the plug P in the jack J, which is associated with the line lamp LL. This results in the establishment of a circuit from ground, battery, the winding of cut-off relay CO, the sleeve of the jack J, sleeve of the plug P, winding of relay 150 to ground. The consequent energization of cut-off relay CO removes the line relay LR and its associated line lamp from the control of the subscriber's line. At the same time the energization of relay 150 completes a circuit from ground, the armature and alternate contact of relay 150, sequence switch contact 101 (position 1), the motor magnet of sequence switch 100 to battery and thence to ground. Sequence switch 100 moves under control of its contact A¹ into its second position.

As sequence switch 100 moves its contacts into the second position, a circuit is established between ground, sequence switch contact 102 (position 2), sequence switch contact 501 (position 1), to the motor magnet of sequence switch 500, battery and thence to ground. Sequence switch 500,

under control of its contact A⁵, moves its contactors into the second position.

The movement of the contactors of sequence switch 500 into the second position results in the establishment of a circuit from ground, battery, the winding of magnet 550, sequence switch contact 502 (position 2), normal contact and right-hand armature of relay 551 and thence to ground. Magnet 550, upon attracting its armature, forces the driving ribbon DR⁵ against the constantly rotating roller 552, whereby the brush carriage B⁵ is elevated. The brushes b¹, b², b³, b⁴ and b⁵ move over and make contact with the associated terminals t¹, t², t³, t⁴ and t⁵. When the brush b² encounters the terminal t² connected with the cord circuit which the operator O has chosen for the extension of the call initiated by the subscriber S, a circuit is established between ground, sequence switch contact 102 (position 2), terminal t², brush b², sequence switch contact 503 (position 2), winding of relay 551 to battery and thence to ground. Relay 551 is energized in this circuit and attracts its armatures, whereby a circuit is established between ground, the right-hand armature and alternate contact of relay 551, sequence switch contact 501 (position 2), the winding of motor magnet of sequence switch 500 to battery and thence to ground. Sequence switch 500 moves its contactors, under control of its contact A⁵, into the third position, thereby opening the energizing circuit of magnet 550 at sequence switch contact 502, and allowing the brushes b¹ to b⁵ to come to rest on the terminals t¹ to t⁵ of the selected cord circuit.

An alternate circuit for the energization of relay 551 is completed upon the attraction of its armatures between ground, battery, the winding of relay 551, sequence switch contact 503 (positions 2 to 11), contact and left-hand armature of relay 551, brush b¹, terminal t¹, sequence switch contact 102 (positions 2 to 11) and thence to ground.

The operator now presses her listening key K, and learning the number of the party wanted by the subscriber at substation S, sets up on her register the number corresponding to that line. Let us assume in this case that the number corresponding to the telephone of the party wanted is 86975—J, the digit 8 representing the office in which the called party's line terminates, the number 6975 representing his line and the letter J representing his station. The operator thereupon presses keys K¹, K², K³, K⁴, K⁵ and K⁶. When the last key, that is, K⁶, has been pressed, a circuit is established from ground, right-hand contact, key K⁶, to a common conductor 670, to which are multiplied the right-hand armatures of relays 671, 672, 673, 674, 675 and 676, the normal con-

tacts of these armatures extending the connection in each case from the common conductor 670 to the motor magnets of sequence switches 610, 620, 630, 640, 650 and 660 respectively, and from there on in each case to battery and thence to ground.

Each one of these sequence switches will thereupon move from the position in which it has now been found to a position determined by the keys K¹ to K⁶ respectively. In the case of sequence switch 610, the movement will continue until the eighth position is reached, upon which a circuit is established from ground, contact of key K¹, sequence switch contact 611 (position 8), the winding of relay 671, battery, and thence to ground. Relay 671 attracts its armatures, thereby opening the energizing circuit for the motor magnet of sequence switch 610. At the same time a circuit is established between ground, battery, the winding of relay 677, to the common conductor 678, alternate contact and armature of relay 671, the common conductor 679 and thence in one direction through the winding of relay 680 to ground, and in the other direction through the left-hand armatures of relays 672 to 676 and thence to ground.

It will be noted that relay 677 is energized in this circuit, but that relay 680 will be short-circuited until each of the left-hand armatures of relays 671 to 676 inclusive has been attracted.

The setting of the thousands register, the hundreds register, the tens register, the units register and the stations register is similar to that described in connection with the setting of the office register, and these settings take place simultaneously. When all are completed the registers will be in the following positions: the office register in position 8; the thousands register in position 6; the hundreds register in position 9; the tens register in position 7; the units register in position 3; and the stations register in position 3.

At this time also the shunt around the winding of relay 680 will be removed and current flowing therethrough will cause its energization. Thereby a circuit will be established from ground, the contact and armature of relay 680, the sequence switch contact 504 (position 3), to the motor magnet of sequence switch 500, battery and thence to ground. Sequence switch 500 moves its contactors, under control of the contact A⁵, into the fourth position.

When the fourth position is reached, a circuit will be established between ground, sequence switch contact 505 (position 4), to the common conductor 681 to which are multiplied the release magnets 682 to 687 inclusive, and from there on to battery and thence to ground in each case. The energization of these release magnets causes the re-

lease of the keys K¹ to K⁶ inclusive, thereby deenergizing the relays 671 to 676 inclusive. Each of these relays retracts its armatures, and in so doing, causes the deenergization of both relays 677 and 680.

70

Relay 677, in retracting its armature, establishes a circuit from ground, contact and armature of relay 677, the sequence switch contact 504 (position 4), the motor magnet of sequence switch 500 to battery and thence to ground. Sequence switch 500, under control of its contact A⁵, moves its contactors into the fifth position. In this position a circuit known as a fundamental circuit, is established, and extends at this time from ground, sequence switch contact 103 (positions 2 to 3) terminal t⁵, brush b⁵, sequence switch contact 506 (position 5), the left-hand armature and contact of counting relay o¹, stepping relay SR, brush b⁴, terminal t⁴, sequence switch contact 104 (position 2), the winding of relay 151 to battery and thence to ground.

75

Relay 151 attracts its armatures, and in so doing, establishes a circuit from ground, left-hand armature and alternate contact of relay 151, sequence switch contact 105 (position 2), the winding of motor magnet of sequence switch 100 to battery and thence to ground. The sequence switch 100, under control of its contact A¹, moves its contactors into the third position, whereupon an alternate circuit for relay 151 is maintained over its contact and right-hand armature, sequence switch contact 104 (positions 2 to 3), 90 and whereby the fundamental circuit is extended through sequence switch contact 104 (position 3), to the commutator segment 155.

80

In position 3 of sequence switch 100, a circuit is established between the ground, 105 left-hand armature and alternate contact of relay 151, sequence switch contact 106 (position 3), the magnet 152 to battery and thence to ground. Magnet 152 attracts its armature and, in so doing, presses the driving ribbon DR¹ against the constantly rotating roller 153, whereby the brush carriage B¹ is elevated. As the brush 154 passes over the first conducting segment of commutator 155, the stepping relay SR is intermittently deenergized and energized.

110

Upon the initial energization of relay SR, a circuit is established between ground, the armature and contact of relay SR, sequence switch contact 516 (position 5), to sequence 120 switch contact 612 (position 8), conductor 553 to the armature and normal contact of relay 8¹, the winding of relay 8 to battery and thence to ground. Relay 8 is thereupon energized, and completes a circuit from ground, sequence switch contact 507 (position 5), armature and contact of relay 8, winding of relay 8¹, winding of relay 8 to battery and thence to ground. Relay 8¹, however, is shunted through the conductor 125 130

553 over the circuit previously traced, and does not energize until relay SR retracts its armature.

When the brush 154 passes over the first 5 segment of commutator 155, relay SR, through the shunt thus established, is de-energized, and thereupon retracts its armature. This results in the energization of relay 8¹, which thereupon transfers the 10 ground, entering the bank of counting relays over conductor 553, through the armature and alternate contact of relay 8¹ to the armature and normal contact of relay 7¹, to the winding of relay 7, to battery and 15 thence to ground. Relay 7 is now energized over the circuit leading from ground, the sequence switch contact 507 (position 5), the armature and contact of relay 7, the winding of relay 7¹ to battery, and thence to 20 ground. In a similar manner each one of the upper counting relays 7¹ to 0¹ is energized by the passing of brush 154 over the 25 segments of commutator 155, and the consequent deenergization of relay SR. When 30 at last counting relay 0¹ is energized, by attracting its left armature, it opens the fundamental circuit, and removes the ground at sequence switch contact 103 (positions 2 to 3) from the circuit leading to the relay 35 151 which is thereby deenergized.

The energization of upper counting relay 0¹ also results in the establishment of a circuit from ground, the right-hand armature and contact of upper counting relay 0¹, sequence switch contact 508 (position 5), the 40 motor magnet of sequence switch 500 to battery and thence to ground. Sequence switch 45 500, under control of its contact A⁵, moves its contactors into the seventh position, whereupon the circuit for energizing the 50 series of counting relays is broken at the sequence switch contact 507 (position 5).

The deenergization of relay 151 results in the establishment of a circuit from ground, 45 left-hand armature and normal contact of relay 151, sequence switch contact 105 (position 3), motor magnet of sequence switch 100, battery and thence to ground. Sequence switch 50 100, under control of its contact A¹, moves from the third into the fifth position.

As relay 151 retracts its armatures, the 55 energizing circuit for the magnet 152 is opened, whereupon the brushes secured to the brush carriage B¹ come to rest before the selected group of trunks.

As position 4 of sequence switch 100 is 60 reached, a circuit is established from ground, sequence switch contact 107 (position 4), and sequence switch contact 107 (positions 4 to 5), sequence switch contact 104 (positions 4 to 5), winding of relay 151 to battery and thence to ground. Relay 151 is energized in this circuit and is held in 65 an energized condition, as sequence switch

100 reaches the fifth position, through a circuit leading from the grounded terminal t⁶ of busy trunks of the group to which the brush carriage B¹ has been directed, through brush b⁶, sequence switch contact 107 (positions 4 to 5) and thence through the circuit previously traced.

In position 5 a circuit is established from ground, the left-hand armature and alternate contact of relay 151, the sequence 75 switch contact 106 (position 5), the winding of magnet 152 to battery and thence to ground. Magnet 152 attracts its armature and causes the elevation of the brush carriage B¹. This elevation continues until the 80 brush b⁶ encounters the terminal t⁶ of an idle trunk, whereupon the holding circuit for relay 151 is broken and the consequent deenergization of this relay causes the opening of the energizing circuit for magnet 152 85 at the alternate contact and left-hand armature of relay 151. The brushes b⁶, b⁷ and b⁸, therefore, come to rest on the terminals t⁶, t⁷ and t⁸ of an idle trunk.

At the same time a circuit is established 90 between ground, left-hand armature and normal contact of relay 151, sequence switch contact 105 (position 5), the winding of motor magnet of sequence switch 100 to battery and thence to ground. Sequence switch 95 100 moves its contactors under the control of contact A¹ into the eleventh position.

As the sixth position is reached, a circuit is established between ground, sequence switch contact 107 (positions 6 to 16), the 100 brush b⁶ and the terminal t⁶, marking the selected trunk as busy.

When at last position 11 of sequence switch 100 is reached, the fundamental circuit is extended to the connecting circuit at 105 the distant exchange, and may now be traced from ground, the sequence switch contact 201 (positions 1 to 4), terminal t⁷, brush b⁷, sequence switch contact 109 (position 11), terminal t⁶, brush b⁶, sequence switch contact 506 (position 7), contact and left-hand armature of the upper counting relay 0¹, winding of stepping relay SR, brush b⁴, terminal t⁴, sequence switch contact 110 (position 11), brush b⁸, terminal t⁸, sequence 115 switch contact 202 (position 1), winding of relay 250 to battery and thence to ground.

Relay 250 is energized in this circuit and attracts its armatures, establishing thereby an alternate circuit for itself extending 120 through the circuit traced as far as sequence switch contact 202 (position 1), at which point it branches and extends through sequence switch contact 202 (positions 1 to 4), left-hand armature and contact of relay 250 125 to battery and thence to ground.

The attraction of its armatures by relay 250 establishes a circuit from ground, right-hand armature and alternate contact of relay 250, sequence switch contact 203 (position 130

1), the winding of motor magnet of sequence switch 200 to battery and thence to ground. Sequence switch 200 moves its contactors under control of its contact A² into the 5 second position.

In position 2 a circuit is established between ground, the right-hand armature and alternate contact of relay 250, the sequence switch contact 204 (position 2), winding 10 of magnet 251 to battery and thence to ground. Magnet 251 attracts its armature and presses the driving ribbon DR² against the constantly rotating roller 252, whereupon the brush carriage B² is elevated. During 15 such elevation, a circuit is established between ground, brush 253, the segments of commutator segment 254, sequence switch contact 202 (position 2), the left-hand armature and contact of relay 250, to battery 20 and thence to ground. The resistance of the path between the sequence switch 202 and the ground at brush 253 is practically zero, while that leading from sequence switch 202, back over the fundamental circuit and 25 through the stepping relay SR is a definite and much higher quantity. The current through the latter part of this circuit is therefore reduced to such a point that stepping relay SR retracts its armature. This 30 occurs each time that brush 253 passes over a segment of the commutator 254.

Upon the first attraction of its armature by the relay SR, a circuit is established from ground, sequence switch contact 516 (position 35 7), the sequence switch contact 661 (position 3), sequence switch contact 621 (position 6), common conductor 554, armature and normal contact of upper counting relay 3', winding of lower counting relay 3, to 40 battery and thence to ground. Lower counting relay 3 attracts its armature, and establishes a circuit between ground, sequence switch contact 507 (position 7), armature and contact of relay 3, winding of relay 3', winding of relay 3', to battery and thence to ground. Relay 3', however, is shunted 45 through the ground entering the bank of counting relays over common conductor 554, and does not attract its armature until the 50 relay SR is deenergized for the first time. When, in response to the brush 253 passing over the first conducting segment of commutator 254, this occurs, then upper counting relay 3' attracts its armature and transfers the ground entering the bank of counting relays over common conductor 554, through its armature and alternate contact to the armature and normal contact of relay 2', thence through the winding of relay 2 to 55 battery and to ground. In the well-known manner, then, each counting relay in turn is energized until at last relay o' attracts its armature, whereupon the fundamental circuit is broken at the left-hand armature 60 and contact of relay o'. 65

A circuit is also established at this time between ground, armature and contact of upper counting relay o', sequence switch contact 508 (position 7), the winding of the motor magnet of sequence switch 500 to battery and thence to ground. Sequence switch 500 moves its contactors under control of its contact A⁵ into the ninth position. 70

The fundamental circuit being opened at the left-hand armature and contact of relay o', and the brush 253 resting on an insulated segment of commutator 254, the relay 250 is deenergized and retracts its armatures. The energizing circuit for magnet 251 is thereupon opened at the right-hand armature 75 and alternate contact of relay 250, and at the same time a circuit is established between ground, the right-hand armature and normal contact of relay 250, sequence switch contact 203 (position 2), the winding of the 80 motor magnet of sequence switch 200 to battery and thence to ground. 85

Sequence switch 200, under control of its contact A², moves its contactors into the third position, thus reestablishing the continuity of the fundamental circuit at the sequence switch contact 202 (position 3). The consequent energization of relay 250 and the attraction of its armatures establishes a circuit between ground, the right-hand armature and alternate contact of relay 250, sequence switch contact 203 (position 3), the winding of motor magnet of sequence switch 200 to battery and thence to ground. Sequence switch 200 moves its contactors, under the control of its contact A², 90 into the fourth position. 95

When the sequence switch 500 moves its contactors from the seventh to the ninth position, the counting relays are restored to 100 their original condition. Now, upon the energization of relay SR, a circuit is established from ground, the armature and contact of relay SR, sequence switch contact 516 (position 9), sequence switch contact 622 (position 6), sequence switch contact 631 (position 9), common conductor 555, the armature and normal contact of upper counting relay 1', winding of lower counting relay 1, to battery and thence to ground. 105 Lower counting relay 1 attracts its armature and establishes a circuit from ground, sequence switch contact 507 (position 9), the armature and contact of lower counting relay 1, the winding of upper counting relay 1', winding of lower counting relay 1 to battery and thence to ground. At this time, however, upper counting relay 1' is shunted 110 in a manner heretofore described, through the ground at the armature and contact of 115 relay SR. Lower counting relay 1 attracts its armature and establishes a circuit from ground, sequence switch contact 507 (position 9), the armature and contact of lower counting relay 1, the winding of upper counting relay 1', winding of lower counting relay 1 to battery and thence to ground. At this time, however, upper counting relay 1' is shunted in a manner heretofore described, through the ground at the armature and contact of 120 relay SR. 125

In position 4 of the sequence switch 200, a circuit is established from ground, right-hand armature and alternate contact of relay 250, sequence switch contact 204 (po- 130

sition 4), the winding of magnet 251 to battery and thence to ground. The energization of relay 251 again forces the driving ribbon DR² against the constantly rotating roller 252 and the brush carriage B² is again elevated.

In position 3 a circuit had been established which is maintained in position 4, from ground, sequence switch contact 205 (positions 3 to 4), the trip magnet TM² to battery and thence to ground. The beginning of the present elevation of the brush carriage B² causes an encounter between the finger F' and the brush tripping mechanism of the selected brushes in a manner substantially similar to that disclosed in the patent heretofore cited. Now, as the elevation of the brushes continues, contact is made first between ground, brush 255, 20 commutator segment 256, but extends no farther, due to the open circuit at sequence switch contact 206 (position 2). The further elevation of the brushes results in a circuit being established between ground, 25 brush 255, the first segment of commutator 257, the sequence switch contact 202 (position 4), sequence switch contact 202 (positions 1 to 4), the winding of relay 250 to battery and thence to ground. This results 30 in the shunting of relay SR, as heretofore described, whereupon relay SR retracts its armature and by thus removing the shunt from around upper counting relay 1', causes the energization of upper counting relay o'. 35 As brush 255 passes off a conducting segment of commutator 257 and on to an insulated segment of commutator 257, relay SR is again energized and in attracting its armature establishes a circuit from ground, 40 sequence switch contact 506 (position 9), sequence switch contact 622 (position 6), sequence switch contact 631 (position 9), common conductor 555, the armature and alternate contact of upper counting relay 45 1', winding of relay o to battery and thence to ground. Lower counting relay o attracts its armature and establishes a circuit between ground, sequence switch contact 507 (position 9), the armature and contact of 50 lower counting relay o, winding of upper counting relay o', the winding of lower counting relay o to battery and thence to ground. Upon the next encounter between brush 255 and the conducting segment of 55 the commutator 257, stepping relay SR is deenergized, and in retracting its armatures, removes the shunt from around upper counting relay o', which therefore attracts its armatures and opens at its left-hand armature the fundamental circuit and closes 60 at its right-hand armature the circuit which extends from ground, right-hand armature and contact of upper counting relay o', sequence switch contact 508 (position 9),

the winding of motor magnet of sequence 65 switch 500 to battery and thence to ground.

Sequence switch 500, under control of its contact A⁵, moves its contactors into the eleventh position, whereupon the energized counting relays are deenergized through the opening of the circuit at sequence switch contact 507 (position 9).

The opening of the fundamental circuit at the left-hand armature of the upper counting relay o' and the movement of the brush 255 to an insulated segment of commutator 257, results in the deenergization of relay 250 which, upon retracting its armatures, opens the energizing circuit for the magnet 251, allowing the brushes b⁹, b¹⁰ and b¹¹ to come to rest before a selected group of trunks. The retraction of its armatures by relay 250 also results in the establishing a circuit from ground, right-hand armature and normal contact of relay 250, sequence switch contact 203 (position 4), the winding of the motor magnet of sequence switch 200 to battery and thence to ground. Sequence switch 200, under control of its contact A², moves its contactors into the fifth position.

In position 5 a circuit is established from ground, sequence switch contact 207 (position 5), sequence switch contact 207 (positions 5 to 6), sequence switch contacts 208 (positions 5 to 6), the winding of relay 250 to battery and thence to ground. Relay 250 is energized in this circuit, and, by attracting its armature, establishes a circuit from ground, right-hand armature and alternate contact of relay 250, sequence switch contact 203 (position 5), the winding of motor magnet of sequence switch 200 to battery and thence to ground. Sequence switch 200, under control of its contact A², moves its contactors into the sixth position.

In this position the relay 250 is maintained in an energized condition through the contact made between brush b⁹ and terminal t⁹, of a busy trunk. In this position also a circuit is established from ground, the right-hand armature and alternate contact of relay 250, sequence switch contact 204 (position 6), the winding of magnet 251 to battery and thence to ground. Magnet 251 attracts its armature and thereby causes the elevation for a third time of the brush carriage B².

The brushes b⁹, b¹⁰ and b¹¹ now move over and make contact with the terminals t⁹, t¹⁰ and t¹¹. When an idle trunk is encountered, the energizing circuit for relay 250 is opened at the terminal t⁹, whereupon relay 250 retracts its armatures, and, by so doing, opens the energizing circuit of relay 251, which in turn allows the brushes b⁹, b¹⁰ and b¹¹ to come to rest upon terminals of the selected idle trunk. Relay 250, in retracting its ar-

matures, also establishes a circuit from ground, the right-hand armature and normal contact of relay 250, the sequence switch contact 203 (position 6), the winding of 5 motor magnet of sequence switch 200 to battery and thence to ground. Sequence switch 200, under control of its contact A², moves its contactors into the seventh position.

In position 7 a circuit is established from 10 ground, sequence switch contact 207 (positions 7 to 17), brush b⁹, terminal t⁹, thus marking the selected trunk as busy.

In this position also the fundamental circuit is reestablished, over which relay 250 15 is again energized. This results in the establishment of a circuit from ground, right-hand armature and alternate contact of relay 250, sequence switch contact 203 (position 7), winding of the motor magnet of 20 sequence switch 200 to battery and thence to ground. Sequence switch 200, under control of its contact A², moves its contactors into the eighth position.

In position 8 a circuit is established from 25 ground, right-hand armature and alternate contact of relay 250, sequence switch contact 204 (position 8), the brush b¹¹, the terminal t¹¹, sequence switch contact 301 (position 1), the winding of relay 351 to 30 battery and thence to ground. Relay 351 attracts its armatures and in turn establishes a circuit from ground, the left-hand armature and alternate contact of relay 351, sequence switch contact 302 (position 1), 35 winding of relay 352 to battery and thence to ground. Relay 352 attracts its armatures, and in its turn establishes a circuit from ground, the lower armature and alternate contact of relay 352, sequence switch contact 303 (position 1), to the motor magnet of sequence switch 300 to battery and thence to ground. Sequence switch 300 under control of its contact A³, moves its contactors into the second position.

45 It should be noted at this point that upon the energization of relay 352 an alternate circuit for this relay is established from ground, battery, winding of relay 352, alternate contact and upper armature of relay 50 352, terminal t⁹, brush b⁹, sequence switch contact 207, (positions 7 to 17) and thence to ground.

The reestablishment of the fundamental circuit results in the extending of a circuit 55 from ground, the armature and contact of relay SR, the sequence switch contact 509 (position 11), sequence switch contact 662 (position 3), sequence switch contact 632 (position 9), common conductor 556, armature and normal contact of upper counting relay 9', winding of lower counting relay 9 to battery and thence to ground. Lower counting relay 9 attracts its armature and establishes a circuit from ground, sequence

switch contact 507 (position 11), armature 65 and contact of relay 9, winding of upper counting relay 9', winding of lower counting relay 9 to battery and thence to ground, in a manner similar to that heretofore described. Relay 9' does not energize at this 70 time, due to the shunt extending back over the common conductor 556 to ground at the armature of the stepping relay SR.

The movement of the contactors of sequence switch 300 into position 2, establishes 75 a circuit from ground, battery, magnet 353, sequence switch contact 302 (position 2), alternate contact and left-hand armature of relay 351 to ground. Magnet 353 presses the driving ribbon DR² against 80 the constantly rotating roller 354, which elevates the brush carriage B³ at a high speed. As the brush carriage B³ is elevated, the brush 355 establishes a connection between ground, the brush 355, the first 85 conducting segment of commutator 356, the sequence switch contact 304 (position 2), the terminal t¹⁰, the brush b¹⁰, the sequence switch contact 209 (position 8), the sequence switch contact 202 (positions 7 to 12), left-hand armature and contact of relay 250 to 90 battery and thence to ground. The circuit just described shunts out the winding of relay SR in a manner heretofore described, and the relay SR, in retracting its armature, 95 removes the shunt from around the upper counting relay 9', which results in the energization of this relay. As the brush 355 continues its travel and next encounters an insulated segment of the commutator 356, stepping relay SR is again allowed to energize, whereupon the ground entering the bank of counting relays over the common conductor 556 is extended through the armature and alternate contact of upper counting relay 9', the armature and normal contact of upper counting relay 8', to the winding of lower counting relay 8, to battery and thence to ground. Lower counting relay 8 is energized and completes a circuit 100 from ground, sequence switch contact 507, armature and contact of relay 8, the winding of upper counting relay 8', the winding of lower counting relay 8 to battery and thence to ground.

105 As brush 355 continues in its upward movement, the counting relays in turn are energized, until at last the energization of the upper counting relay 9' results in the opening of the fundamental circuit and the movement of the sequence switch 500 into position 115 120 125 130 135 140 145 150 155 160 165 170 175 180 185 190 195 200 205 210 215 220 225 230 235 240 245 250 255 260 265 270 275 357, commutator segment 359, sequence switch contact 306 (position 2), winding of relay 360, battery and thence to ground. Relay 360 attracts its armatures and completes a locking circuit for itself which extends from ground, the right-hand armature and both contacts of relay 360, sequence switch contact 306 (positions 2 to 13), winding of relay 360, battery and thence to ground.

The opening of the fundamental circuit results in the deenergization of relay 250, which, upon retracting its armatures, completes a circuit from ground, the right-hand armature and normal contact of relay 250, sequence switch contact 203 (position 8), the winding of motor magnet of sequence switch 200 to battery and thence to ground. Sequence switch 200, under control of its contact A², moves its contactors into the ninth position. At the same time the removal of the ground from the alternate contact of relay 250 results in the deenergization of relay 351, which in turn results in the deenergization of the up-drive magnet 353.

The deenergization of relay 351 also results in the establishment of a circuit from ground, the armature and normal contact of relay 351, sequence switch contact 303 (position 2), the winding of motor magnet of sequence switch 300 to battery and thence to ground. Sequence switch 300, under control of its contact A², moves its contactors into the third position.

As sequence switch 300 reaches position 3, a circuit is established from ground, sequence switch contact 305 (positions 3 to 4), trip magnet TM³, to battery and thence to ground. Trip magnet TM³ attracts its armature and brings the fingers F³ and F⁴ in the path of the tripping mechanism of the brush carriage B³.

As sequence switch 200 reaches the ninth position, the fundamental circuit is reestablished, and the consequent energization of the relay 250 drives the sequence switch 200 into its tenth position in the manner heretofore described, whereupon the circuit for the energization of relay 351 is established through sequence switch contact 301 (position 3). The consequent energization of relay 351 results in the attraction of its armatures, and the establishment of a circuit from ground, the left-hand armature and alternate contact of relay 351, sequence switch contact 303 (position 3), the winding of motor magnet of sequence switch 300 to battery and thence to ground. Sequence switch 300 moves its contactors, under the control of contact A³, into the fourth position, in which a circuit is established from ground, the left-hand armature and alternate contact of relay 351, sequence switch contact

302 (position 4), the winding of up-drive 65 magnet 353 to battery and thence to ground. Magnet 353 attracts its armature and presses the driving ribbon DR³ against the constantly rotating roller 354, whereby brush carriage B³ is elevated again at a high speed. Upon its first movement in this direction, the finger F⁴ comes in contact with the brush tripping mechanism of the selected brushes, in a manner similar to that heretofore described.

It should be noted here that both fingers F³ and F⁴ are arranged to trip the same set of brushes, and that the selection of one or the other for this service depends on whether or not the regular number of brush 80 tripping impulses have been transmitted. In this case, an additional five impulses have been sent, and the brush carriage has, therefore, been driven into the second brush tripping zone.

When, upon the movement of the sequence switch 200 into position 9, the fundamental circuit was again reestablished, the stepping relay SR was energized. A circuit was thereupon extended from ground, the armature and contact of stepping relay SR, the sequence switch contact 509 (position 13), the sequence switch contact 641 (position 7), the common conductor 557, the armature and normal contact of upper counting relay 7, the winding of lower counting relay 7 to battery and thence to ground. Lower counting relay 7 attracts its armature and establishes a circuit from ground, sequence switch contact 507 (position 13), the armature and contact of lower counting relay 7, the winding of upper counting relay 7, the winding of lower counting relay 7 to battery, and thence to ground. Upper counting relay 7, however, is shunted at this time through ground at the contact and armature of the relay SR, and stays energized until the relay SR has been deenergized.

As the brush carriage B³ is, therefore, further elevated, a circuit is established between brush 357, the first conducting segment of the commutator 358, the sequence switch contact 304 (position 4), the terminal t¹⁰, the brush b¹⁰, the sequence switch contact 209 (position 10), the sequence switch contact 202 (positions 7 to 12), left-hand armature and contact of relay 250, the winding of relay 250 to battery, and thence to ground. Through this circuit the stepping relay SR is deenergized in a manner similar to that heretofore described.

The elevation of brush carriage B³ continues until the proper group of brushes has been selected in response to the successive operation of the counting relays, at which time the fundamental circuit is opened at the left-hand armature and contact of upper

counting relay o' . This results again in the deenergization of relay 250, and the consequent deenergization of relay 351.

At the same time a circuit is established 5 between ground, the right-hand armature and contact of upper counting relay of o' , the sequence switch contact 508 (position 13), to the motor magnet of sequence switch 500, battery, and thence to ground. Sequence switch 500, under control of its contact A^5 , moves its contactors into the fifteenth position.

The deenergization of relay 250 results in 15 the establishment of a circuit between ground, the right-hand armature and normal contact of relay 250, sequence switch contact 203 (position 10), winding of motor magnet of sequence switch 200 to battery and thence to ground. Sequence switch 200, 20 under control of its contact A^2 , moves its contactors into the eleventh position.

The deenergization of relay 351 results in 25 the opening of the energizing circuit for magnet 353 and the establishment of a circuit from ground, the left-hand armature and normal contact of relay 351, sequence switch contact 303, (position 4), the winding of motor magnet of sequence switch 300 to battery and thence to ground. Sequence switch 300, 30 under control of its contact A^3 , moves its contactors into the fifth position.

The movement of the sequence switch 200 into position 12 is accomplished by the re-establishment of the fundamental circuit 35 through the sequence switch contact 202 (position 11), and the consequent energization of relay 250. Relay 250, in attracting its armatures, establishes a circuit from ground, the right-hand armature and alternate contact of relay 250, sequence switch contact 203 (position 11), winding of motor magnet of sequence switch 200 to battery, and thence to ground. Sequence switch 200 under control of its contact A^2 , moves its 40 contactors into the twelfth position.

In position 12, a circuit is established from ground, right-hand armature and alternate contact of relay 250, sequence switch contact 204 (position 12), brush b^{11} , terminal t^{11} , 50 sequence switch contact 301 (position 5), winding of relay 351 to battery, and thence to ground. Relay 351 attracts its armatures, and thereby establishes a locking circuit for itself, extending through the circuit traced 55 up to the sequence switch contact 301 (position 5), where it branches and extends through sequence switch contacts 301 (positions 1 to 6), the right-hand armature and contact of relay 351 to battery, and thence to ground.

The energization of relay 351 also results in the establishment of a circuit from ground, left-hand armature and alternate contact of relay 351, sequence switch contact

303 (position 5), and winding of motor magnet of sequence switch 300 to battery, and thence to ground. Sequence switch 300, under control of its contact A^3 , moves its contactors into position 6.

In position 6 a circuit is established from 65 ground, the left-hand armature and alternate contact of relay 351, the sequence switch contact 302 (position 6), the winding of magnet 361 to battery, and thence to ground. Magnet 361 attracts its armature and presses 75 the driving ribbon DR³ against the constantly rotating roller 362 which thereby, elevates the brush carriage B³ at a low speed.

Upon the last energization of the stepping relay SR which took place when sequence 80 switch 200 moved its contactors into the eleventh position, a circuit is established from ground, the armature and contact of relay SR, the sequence switch contact 509 (position 15), the sequence switch contact 651 (position 5), the common conductor 558, through the armature and normal contact of upper counting relay 5', and the winding of lower counting relay 5 to battery, and thence to ground. In the elevation of the 85 brush carriage B³, the brush 355 intermittently makes contact with the conducting segments of the commutator 356, whereby a circuit is extended from ground, the brush 355, the commutator 356, the sequence switch contact 304 (position 6), the terminal t^{10} , the brush b^{10} , the sequence switch contact 209 (position 12), and thence through the fundamental circuit, and the winding of relay 250 in a manner similar to that previously described. The stepping relay SR is intermittently shunted and caused to retract its armatures, whereby the counting 90 relays are successively energized until upper counting relay o' is reached, at which time 95 the fundamental circuit is opened.

The opening of the fundamental circuit by the energization of upper counting relay o' results in the movement of the sequence switch 500 into position 16, and also results 100 in the deenergization of relay 250.

As sequence switch 500 reaches position 16, a circuit is established between ground, the sequence switch contact 510 (position 16), brush b^3 , terminal t^3 , sequence switch contact 105 (position 11), to the winding of motor magnet of sequence switch 100 to battery, and thence to ground.

Sequence switch 100, under control of its contact A^1 , moves its contactors into the sixteenth position, whereupon the talking conductors of the selected connecting circuit are extended through the first selector at the sequence switch contacts 109 (positions 12 to 16) and 110 (positions 12 to 16).

As sequence switch 100 moves out of position 11, a circuit through which relay 551 is held energized, is opened at the sequence

switch contact 102 (positions 2 to 11), resulting in the deenergization of this relay. A circuit is thereupon established between ground, the right-hand armature and normal contact of relay 551, the sequence switch contact 501 (positions 3 to 16), the winding of motor magnet of sequence switch 500 to battery, and thence to ground. Sequence switch 500, under control of its contact A⁵, 10 moves its contactors into the seventeenth position.

In position 17, a circuit is established between ground, sequence switch contact 511 (position 17), winding of magnet 559, battery, and thence to ground. Magnet 559 attracts its armature, and thereby presses the driving ribbon DR⁵ against the constantly rotating roller 560, whereby the brush carriage B⁵ is caused to return to normal position. 15

When this normal position has been reached, a circuit is established between ground, the brush 561, the commutator 562, the sequence switch contact 508 (position 25 17), the winding of motor magnet of sequence switch 500 to battery, and thence to ground. Sequence switch 500, under control of the contact A⁵, moves its contactors into the first or normal position, at which 30 time it is ready to perform the functions heretofore described in connection with any other cord circuit which the operator may select for the initiation of another call.

The deenergization of relay 250 now results in the establishment of a circuit from ground, the right-hand armature and the normal contact of relay 250, the sequence switch 203 (position 12), the winding of motor magnet of sequence switch 200 to battery, and thence to ground. Sequence switch 200, under control of its contact A², 35 moves its contactors into the sixteenth position, whereupon the talking circuit extended from the operator's connecting circuit through first selector is now extended to the connecting circuit at the second selector through sequence switch contact 201 (positions 13 to 17) and sequence switch contact 209 (positions 13 to 17).

50 The deenergization of relay 250 also results in the deenergization of relay 351, and, in turn, the deenergization of magnet 361, whereby the elevation of brush carriage B³ is halted and the brushes b¹², b¹³ and b¹⁴ 55 are brought to rest on the terminals t¹², t¹³ and t¹⁴ of the selected subscriber's line.

Upon the extension of the operator's connecting circuit shown in Fig. 1 to the connecting circuit diagrammatically shown in 60 Fig. 2, a circuit is completed between ground, the upper right-hand winding of repeated coil RC¹, the sequence switch contact 110 (position 16), the brush b⁸, the terminal t⁸, the sequence switch contact 209

(positions 13 to 17), the upper left-hand winding of repeating coil RC², the winding of relay 258 to battery, and thence to ground. Relay 258, therefore, attracts its armature before position 16 has been reached, and thereby prevents the establishment of a circuit to drive the sequence switch 200 into a further position, as will be described hereafter. 65 70

The last deenergization of relay 351 resulted, in addition to the opening of the circuit for magnet 361, in the establishment of a circuit from ground, the left-hand armature and normal contact of relay 351, the sequence switch contact 303 (position 6), the winding of the motor magnet of sequence switch 300, to battery and thence to ground. Sequence switch 300, under control of its contact A³, moves its contactors into the thirteenth position. In position 13, however, a circuit is extended from ground, the right-hand armature and first contact of relay 360, the sequence switch contact 307 (position 13), through the winding of motor magnet 300 to battery, and thence to ground. Sequence switch 300, therefore, moves its contactors, under the control of its contact A³, into the fourteenth position, in which relay 360 is deenergized. 80 85 90

When position 10 of sequence switch 300 is reached, a circuit is established from ground, sequence switch contact 308 (positions 10 to 16), to the brush b¹², the terminal t¹² of the selected line, whereupon this line is marked as busy. 95

As sequence switch 200 reaches position 16, a circuit is established from ground, the sequence switch contact 212 (position 16), the contact and armature of relay 259, contact and armature of relay 260, the winding of relay 261 to battery, and thence to ground. Relay 261 is energized in this circuit and attracts its armature. 100 105

It should be noted at this point that the signaling system described herein is the well known Thompson and Rodes party line system, described in U. S. Patent 644,647 and in Kempster B. Miller's "American Telephone Practice," pages 439 to 441. It should be further noted that a particular method of ringing subscribers' bells is not an essential part of the invention and that other systems than that shown might be employed without departing from the spirit of the invention. 110 115

The called subscriber's bell is now rung through current flowing over the circuit extending from a source of plus pulsating current, the left-hand armature and normal contact of relay 262, the winding of relay 259, the lower armature and alternate contact of relay 261, sequence switch contact 210, the brush b¹⁰, the terminal t¹⁰, the left-hand armature and contact of relay 360, the se- 120 125

quence switch contact 309 (position 14), the brush b^{14} , the terminal t^{14} , over the upper limb of the subscriber's line, in parallel through each one of the condensers at the 5 substations S^J , S^R , S^F and S^W , the winding of the relays at each one of these stations, thence through the secondary of the induction coils at each one of these stations, and then to the lower limb of the subscriber's 10 line, the terminal b^{13} , the brush b^{13} , the sequence switch contact 310 (position 14), the terminal t^{11} , the brush b^{11} , sequence switch contact 211 (positions 14 to 16), the alternate contact and upper armature of relay 15 261 to ground. The four relays at the subscriber's substations will be energized in this circuit and will attract their armatures, whereupon the ringing current flowing out over the upper limb of the subscriber's line 20 will find a parallel path extending through the condensers, armatures, contacts of the substation relays, and bells of the substations S^R and S^J to ground. This current will not flow through the bells of the stations S^F 25 and S^W since the lower limb on the subscriber's line extends to a ground at the upper armature and alternate contact of relay 261, which ground acts as a shunt around these bells.

30 It should be noted that the bells at substations S^R and S^J are arranged to respond to currents of different characters, that at the substation S^R responding to minus pulsating current, and that at the substation S^J 35 responding to plus pulsating current. The current being supplied to these lines is of plus pulsating current, hence, of the four bells shown, only that at the station S^J will respond.

40 Now the plus pulsating current flowing out over the circuits described to actuate the four relays at the four subscribers' substations and the bell at substation S^J is not sufficiently large to cause the energization of 45 relay 259. When, however, the subscriber at substation S^J , in response to the summons of his bell, removes the receiver from its switch-hook, a path of low resistance is bridged across the telephone line, and the increase in 50 flow of plus pulsating current is sufficient to cause the energization of relay 259. Thereupon, the circuit heretofore described for the energization of relay 261 is opened at the armature and contact of relay 259, and may 55 now be traced from ground, the sequence switch contact 212 (position 16), the winding of relay 260, the winding of relay 261 to battery, and thence to ground. Relay 260 attracts its armature and completes a locking circuit for itself from ground, battery, the alternate contact and armature of relay 60 260 through the winding of relay 260, sequence switch contact 212 (position 16), to ground.

Relay 261 is shunted in this circuit and retracts its armatures, whereupon the ringing current is disconnected from the subscriber's line, and a talking circuit is established, extending from the repeating coil RC^2 to the substation S^J . This circuit may be traced 65 from ground, the upper right-hand winding of repeating coil RC^2 , the normal contacts of the upper armature of relay 261, the sequence switch contact 211 (position 16), the brush b^{11} , the terminal t^{11} , the sequence 70 switch contact 310 (position 14), the brush b^{13} , the terminal t^{13} , to the lower limb of the telephone line, thence through the apparatus of the substation S^J , the upper limb of the telephone line, to the terminal t^{14} , the brush b^{14} , the sequence switch contact 309 75 (position 14), the contact and armature of relay 360, the terminal t^{14} , the brush b^{14} , sequence switch contact 210 (position 16), the lower armature and contact of relay 261, the 80 winding of supervisory relay 263 to the lower right-hand winding of repeating coil RC^2 to battery, and thence to ground. 85

Current flowing over this circuit energizes the supervisory relay 263, and a circuit is thereby established from ground, the armature and contact of relay 263, the impedance coil 264, the lower left-hand winding of repeating coil RC^2 , the sequence 90 switch contact 201 (positions 13 to 17), terminal t^6 , brush b^6 , sequence switch contact 109 (positions 12 to 16), supervisory relay 156, the lower right-hand winding of repeating coil RC^1 to battery, and thence to 95 ground. Supervisory relay 156 thereupon 100 signals the operator in the well-known manner that the called subscriber has answered his telephone.

When the conversation over this circuit 105 has been completed, the subscriber at substation S^J , in replacing his receiver on its hook, deenergizes supervisory relay 263, which, in turn, deenergizes supervisory relay 156.

The subscriber at substation S in replacing his receiver on its hook in a well-known manner deenergizes the supervisory relay 157. The resulting signals are displayed before the operator and are recognized by her as a signal to disconnect. She thereupon removes the plug P from the jack J , which results in the deenergization of relay 150. 110

Relay 150 upon retracting its armature establishes a circuit from ground, the right-hand armature and normal contact of relay 150, the sequence switch contact 101 (positions 2 to 17), the winding of motor magnet of sequence switch 100 to battery, and thence to ground. Sequence switch 100, under control of its contact A^1 , moves its contactors 115 to the eighteenth position. 120

In position 18 a circuit is established from ground to sequence switch contact 103 (position 18), the winding of magnet 158, bat-

battery, and thence to ground. Magnet 158 attracts its armature and presses the driving ribbon DR¹ against the constantly rotating roller 159, whereby the brush carriage B¹ is caused to return to a normal position. When this position has been reached, a circuit is established from ground, brush 154, commutator segment 160, sequence switch contact 105 (position 18), the winding of motor magnet 100, to battery, and thence to ground. Sequence switch 100, under control of its contact A¹, moves its contactors into the first or normal position, whereupon the first selector is fully restored.

15 As the sequence switch 100 passes out of position 16, a circuit heretofore described for the energization of relay 258 is opened at the sequence switch contact 110. The consequent deenergization of relay 258 establishes a circuit for ground, armature and contact of relay 258, the sequence switch contact 203 (position 16), the winding of motor magnet of sequence switch 200 to battery, and thence to ground. Sequence switch 200, under control of its contact A², moves its contactors into the eighteenth position.

In position 18 of the sequence switch 200, a circuit is established from ground, sequence switch 205 (position 18), the winding of magnet 265 to battery and thence to ground. Magnet 265 attracts its armature and presses the driving ribbon DR² against the constantly rotating roller 260, whereupon the brush carriage B² is caused to return to normal position. When this position is reached, a circuit is established from ground, brush 255, commutator segment 267, sequence switch contact 203 (position 18), 40 through the winding of motor magnet of sequence switch 200 to battery, and thence to ground. Sequence switch 200, under control of its contact A², moves into the first or normal position, whereupon the second selector is fully restored.

When sequence switch 200 moves out of position 17, the circuit for maintaining relay 352 energized was broken at the sequence switch contact 207. Relay 352, upon retracting its armatures, establishes a circuit from ground, the lower armature and normal contact of relay 352, the sequence switch contact 307 (positions 2 to 17), the winding of motor magnet of sequence switch 300 to battery, and thence to ground. Sequence switch 300, under control of its contact A³, moves into the eighteenth position.

In position 18 a circuit is established from ground, the sequence switch contact 305 (position 18), the winding of magnet 363 to battery, and thence to ground. Magnet 363 attracts its armature and presses the driving ribbon DR³ against the constantly rotating roller 364, whereupon the connector switch 65 is moved to its normal position. When this

normal position is reached, a circuit is established between ground, brush 357, the commutator segment 365, the sequence switch contact 307 (position 18), the winding of motor magnet of sequence switch 300 to battery, and thence to ground. Sequence switch 300, under control of its contact A³, moves into the first or normal position, whereupon this connector switch is fully restored.

Referring now especially to Fig. 3, it should be noted that while the sequence switch 300 was in position 2 that ten brush selecting impulses were sent. Now there are five sets of brushes on such a switch which are so arranged here that each may be selected through the transmission of two sets of impulses one consisting of five or less and the other consisting of five plus five or less. For instance the first set of brushes may be selected through either one or six impulses and the fifth set may be selected through either five or ten impulses. In this case ten impulses were set whereby the fifth set of brushes was selected in the second of the two ways possible. The choice of the second way resulted in the energization of relay 360 which prevented the sequence switch from resting in position 13 and thereby resulted in a reversal of the line conductors at sequence switch contacts 309 and 310. It should be noted that the energization of relay 360 was not accomplished until the brush 355 had passed over five of the conducting segments of commutator 356, this being a measure of the distance between the commutator 359 and the normal position of the brush 357.

If the sequence switch 660 had been set in position 1 instead of position 3, then the brush selecting impulses would have been determined by a circuit, part of which may be traced from sequence switch contact 662 (position 1), sequence switch contact 633 (position 9), common conductor 563 to the armature and normal contact of upper counting relay 4' and so forth, whereby five instead of ten impulses would have been sent. In such a case the relay 360 would not have been energized and the sequence switch 300 would have rested in position 13 during the period of conversation.

Similarly five extra impulses might have been sent in selecting the brushes of the selector B². This would have caused brush 255 to travel over a commutator segment 256, which would have completed a circuit from ground, brush 255, commutator segment 256, sequence switch contact 206 (position 2), through the winding of the relay 262 to battery and ground. The relay 262 would then have become energized and closed at its right-hand armature a locking circuit for itself. At its left-hand armature it would have changed the character of the

ringing current from plus pulsating to minus pulsating current so that the station S^r would have been rung instead of the station S^j.

5. It will therefore be seen from the foregoing description that through the provision of a double brush tripping zone and the provision of a double set of brush tripping fingers that a selection of ringing current 70
10. may be made at one selector switch and a reversal of the talking conductors made at a subsequent connector switch, whereby any one of four different parties may be selectively summoned.

15. What is claimed is:

1. In a telephone system, a telephone line, means including an automatic selective switch for extending a connection to said line, a plurality of series of corresponding 75
20. selective positions for said switch, means for causing said device to effect the same connection in a plurality of corresponding positions, said means including a plurality of corresponding actuating members, a source of current, and means responsive to the movement of said selective switch to different corresponding positions for differently applying said current to said line. 80
25. 2. In a telephone system, a telephone line, means including an electrically operated selecting device for extending a connection to said line, two series of corresponding selective positions for said device, means including a separate actuating member for rendering said device operative in each position, said device being arranged to effect the same line selecting operation when moved to either of its corresponding positions, a source of current, and means dependent on 85
30. 35. 40. whether said selecting device is positioned in one of its first or second series of positions for differently applying said current to said line.

3. In a telephone system, a calling line, a called line, a plurality of stations on said called line, a signaling device at each of said stations respectively, differently responsive to ringing current, means including a rectilinearly movable connector switch for 90
45. establishing a connection from one of said lines to the other, a single terminal set for said called line at said switch, a source of ringing current, means controlled solely by said switch in making connection to said 95
50. 55. terminal set for joining said source to one or the other talking conductor terminals of the said line.

4. In a telephone system, a calling line, a called line, a plurality of stations on said 100
60. called line, signaling devices at said stations differently responsive to ringing current, means including a connector switch for establishing a connection from one of said lines to the other, a single terminal set for 105
65. said called line at said switch, a source of 110
115. 120. 125. 130.

ringing current, and means including a separate actuating member for controlling said switch in each selective position thereof in making connections with said terminal set for joining said source to one or the other 70 talking conductor terminals of said line.

5. In a telephone system, a telephone line, means including an electrically operated switch controlling device for extending a connection to said line, a plurality of series 75
75. of corresponding selective positions for said device, means including a separate actuating member for rendering said device operative in each position, said device being arranged to effect in corresponding positions the same 80 switching operation, a source of current, and means dependent on to which of its corresponding positions said selecting device has been moved for differently applying said current to said line. 85

6. In a telephone system, a telephone line, means including a rectilinearly movable selective switch for extending a connection to said line, a plurality of brushes on said switch, a device having a plurality of actuating members corresponding to a plurality of selective positions of said brushes, a source of current, and means dependent on whether said brushes have been operated in one or another of its selective positions for 90
95. differently associating said source of current with said line.

7. In a telephone system, a telephone line, means including an automatic selective switch for extending a connection to said line, a plurality of sets of brushes on said switch, means for selecting a desired one of said sets of brushes, said means including a plurality of actuating members for selecting the same set of brushes, a source of current, and means dependent on the manner in which said brushes are selected for differently associating said source of current with said line. 100
105

8. In a telephone system, a telephone line, means including a rectilinearly movable selective switch for extending a connection to said line, a plurality of sets of brushes on said switch, a brush selecting device, means for moving said sets of brushes into a plurality of corresponding selective positions, a source of current, and means dependent on whether said sets of brushes have been moved to one or another of its corresponding positions for differently associating said source of current with said line. 110
115
120

9. In a telephone system, a telephone line, means including a rectilinearly movable switching device for extending a connection to said line, electrically operated means for moving said device into a plurality of sets of corresponding selective positions, said device being arranged to effect the same switching operation when in each of its 125
130.

corresponding positions, a source of current, and means controlled by said device in passing into a selected position for joining one or another pole of said source of current to said line.

- 5 10. In a telephone system, a telephone line, means including a mechanically operated switch for extending a connection to said line, selective means at said switch capable of actuating said switch in a plurality of corresponding selective positions, said selective means including a separate actuating member for each position, the selection accomplished at corresponding positions being the same, a source of current, and means dependent on whether said selective switch is actuated in one or another of its selective positions for differently applying said current to said line.

- 10 15 20 25 30 35 40 45 50 55 60 65 70 75 80 85 90 95 100 105 110 115 120 125 130
11. In a telephone system, a telephone line, means including a multi-brush switch for extending a connection to said line, a plurality of brush selecting positions for said switch, means including a separate actuating member for the selection of brushes in each position, the brushes selected at corresponding positions being the same, a source of current, and means dependent on whether said brushes have been selected in one or another corresponding position for differently applying said current to said line.

12. In a telephone system, a telephone line, means including a multi-brush switch for extending a connection to said line, a rotatable brush selecting device at said switch, a plurality of selective positions for said switch, said brush selecting devices having a separate member for actuating said brushes in each selective position, the brush selected at corresponding positions of said switch being the same, a source of current, and means dependent on whether said selecting device has selected a set of brushes in one or another position for differently applying said current to said line.

13. In a telephone system, a telephone line, means including a multi-brush connector switch for establishing a connection to said line, a brush selecting device including a plurality of actuating members at said switch, a single terminal set for said line at said switch, controlling means for said brush selecting device differently operated to cause said brush to be selected by one or another of said actuating members, a source of ringing current, means for moving the selected brush set into engagement with said terminal set, and means dependent on the position in which said brushes have been selected for joining said current to one or the other of the talking conductors of said line.

14. In a telephone system, a calling line, 65 a called line, two telephone stations on said

called line, a signaling device at each of said stations respectively, said signaling devices being connected one to each of the conductors of said called line, means including a multi-brush rectilinearly movable connector switch for establishing a connection from said calling to said called line, a brush selecting device at said switch including a plurality of actuating members, a single terminal set for said called line at said switch, controlling means for said selecting device differently operated to cause said device to select in a plurality of positions the brush set having access to said terminal set, means for moving said selected brush set to make connection to said terminal set, a source of ringing current, and means dependent on the position in which said brush set has been selected for joining said source of current to one or the other of the conductors of said called line.

15. In a telephone system, a telephone line, two stations on said line, signaling devices at each of said stations respectively, said signaling devices being connected one to each of the conductors of said line, means including a multi-brush rectilinearly movable switch for establishing a connection to said line, a single terminal set for said line at said switch, a brush selecting device at said switch comprising a rotatable shaft and a plurality of brush tripping members, said members being arranged to trip the same set of brushes when said switch is in different positions, controlling means for said brush tripping device for causing it to assume a position to trip the brush set having access to said terminal set, means for moving the selected brush set into engagement with said terminal set, a source of current, and means dependent on whether said brushes have been tripped in one or another position for joining said source to one or the other of the conductors of said line.

16. In a telephone exchange system, a telephone line, two stations on said line, signaling devices at said stations, respectively, said signaling devices being connected one to each of the conductors of said line, means including a multi-brush rectilinearly movable switch for establishing connection to said line, a brush tripping device at said switch capable of tripping the same set of brushes in one or more positions thereof, controlling means for said brush tripping device for causing it to select the brush having access to said telephone line, a source of current, and means dependent on the position in which said brush set was tripped for joining one or the other poles of said source to said line.

17. In a telephone system, a telephone line, two stations on said line, signaling devices at said stations respectively, said signaling devices being connected one to each

of the conductors of said line, means including a multi-brush rectilinearly movable switch for establishing a connection to said line, a brush selecting device at said switch 5 comprising a plurality of brush tripping members so arranged that the same set of brushes will be tripped in several positions thereof, a single terminal set for said called line at said switch, controlling means for 10 causing said device to select the brush set having access to said terminal set, means for moving the selected brush set into engagement with said terminal set, a source of current, and means dependent on the position 15 in which said brush set was selected for joining said source of current to one or the other of the conductors of said line.

18. In a telephone system, a multi-brush rectilinearly movable switch, a brush selecting device comprising a rotatable shaft and a plurality of brush tripping members, means for actuating said device, a plurality of corresponding brush selecting positions of said switch, said brush selecting device being arranged to select the same brush when said switch is moved to corresponding positions, a switching device, means for causing the operation of said switching device if said brushes are selected in one position, and 30 means whereby said switching device will not be operated if said brushes are selected in another position.

19. In a telephone system, a multi-brush rectilinearly movable switch, a plurality of 35 sets of brushes included in said switch, a brush set selecting device including a plurality of brush tripping members, means for causing said brush set selecting device to actuate the same set of brushes in corresponding positions thereof, a relay, means for causing the energization of said relay if 40 said set selecting device is made operative in one position of said brush set, and means whereby said relay will not be energized if 45 said brush set selecting device is made operative in another of said positions.

20. In a telephone system, a multi-brush rectilinearly movable switch, a rotatable brush selecting device, means for causing 50 said device to assume a position to select a certain desired brush in several positions thereof, a relay, means for energizing said relay if said selecting device is actuated in one position of said brush, and means whereby 55 said relay will not be energized if said selecting device is actuated in another of said positions of said brush.

21. In a telephone system, an electrically operated rectilinearly movable switching device, several selecting positions for said device separated from each other by a definite linear distance, a relay, and means for energizing said relay only when said switching device is moved through the complete distance of a selecting position, or more. 65

22. In a telephone system, an electrically operated rectilinearly movable switching device, a series of selecting positions for said device, said positions being separated from one another by definite linear distances, the 70 selection effected in corresponding positions of said series being the same, a relay, and means controlled by said switching device in passing one of its series of positions to the next for energizing said relay. 75

23. In a telephone system, a telephone line, means including an electrically operated rectilinearly movable switching device for establishing a connection to said line, an operator's sending device including a register having a plurality of series of corresponding contacts, the corresponding contacts in the two series being arranged to control the sending of the different series of impulses, means for operating said selecting 85 device under the control of corresponding contacts from either of said sets to effect the said selecting operation, and an additional register for determining which of the sets of contacts of the first mentioned register will be operated. 90

24. In a telephone system, a telephone line, means including an automatic selective switch for establishing a connection to said line, an operator's sending device for controlling said switch, two normally deenergized relays for controlling said sending device, a link circuit between the said two relays comprising a multiple of switches, one of said relays being responsive to the actuation of one or more of said link circuit switches and the other of said relays being responsive only to the actuation of all of said link circuit switches. 95

25. In a telephone system, a telephone line, means including an automatic selective switch for establishing a connection to said line, an operator's sending device for controlling said switch, a control circuit for said sending device including two relays 100 and a link circuit between said relays comprising a plurality of switches connected in multiple, one of said relays being responsive to the actuation of one or more of said link circuit switches and the other of said relays 110 being responsive only to the actuation of all of said link circuit switches. 115

26. In a telephone system, a telephone line, means including automatic selective switches for establishing a connection to said line, an operator's sending device for controlling said switches, means for controlling said sending device including two relays and a link circuit extending between said relays, said link circuit comprising a plurality of switching devices, one of said relays being responsive to the actuation of one or more of said devices and the other of said relays being responsive only to the actuation of all of said devices. 120 125 130

27. In a telephone system, a telephone line, means including an automatic selective switch for establishing a connection to said line, an operator's sending device for controlling said switch including a register and control means therefor, said register control means including two magnets joined by a link circuit comprising a plurality of switching devices, one of said magnets being responsive to the actuation of one or more of said switching devices, and the other of said magnets being responsive only to the actuation of all of said switching devices.
- 15 28. In a telephone system, a telephone line, a rectilinearly movable automatic selective switch, a plurality of series of fixed

contacts for said switch, movable contacts arranged to engage a selected series of fixed contacts, two series of corresponding selective positions for said switch, the brushes of said switch being arranged to engage the same series of contacts when said switch is moved to either of its corresponding positions, a source of current, and means dependent on whether said selective switch is positioned in one of its first or second series of positions for differently applying said current to said line.

In witness whereof, I hereunto subscribe my name this 29th day of November A. D., 1916.

ALBEN E. LUNDELL.
